UNITED STATES PATENT OFFICE.

BURTON L. HUNTLEY, OF MINNEAPOLIS, MINNESOTA, ASSIGNOR, BY DIRECT AND MESNE ASSIGNMENTS, TO KREAMPAK CARTON CO., OF MINNEAPOLIS, MINNESOTA, A CORPORATION OF DELAWARE.

ICE-CREAM-CARTON FILLER.

Application filed April 1, 1925. Serial No. 19,833.

My present invention provides an extremely simple and highly efficient ice-cream carton filling device and, generally stated, the invention consists of the novel construction, 5 arrangement and combinations of devices hereinafter described and defined in the claims.

The invention is illustrated in the accompanying drawings, wherein like characters 10 indicate like parts throughout the several views.

Referring to the drawings:

Fig. 1 is a side elevation showing the complete device, some parts being broken away;

Fig. 2 is an axial section of the device, the handle thereof being broken away;

Fig. 3 is a horizontal section on the line 3—3 of Fig. 1;

Fig. 4 is a horizontal section on the line 20 4—4 of Fig. 1;

Fig. 5 is an enlarged fragmentary section on the line 5—5 of Fig. 2; and

Fig. 6 is a plan view showing a combined 25 scraper and clamping ring adapted to be used in connection with the device.

The character A indicates a cylindrical paper carton adapted to be filled with ice-cream. This carton, as shown, is of a long size capable of holding, say, one quart of 30 ice-cream, but the device, as will hereinafter be noted, is capable of handling shorter or half-length paper cartons adapted to contain each a pint of ice-cream. The paper carton is arranged to be placed within a cylindrical metal shell, which, to contain the long or quart size carton A, is shown as made up of two metal cylinders 7 and 8 of the same diameter and adapted to be connected and operated as a single casing by 35 interlocking joints, such as bayonet joints. These bayonet joints, preferably, are formed by L-shaped lugs 9 projected from the lower edge of the upper cylinder 7 and detachably engageable with L-shaped notches 10 in the 40 upper portion of the lower cylinder 8.

A cylinder head is adapted to be clamped, at will, either to the upper portion of the lower cylinder 8 or to the upper portion of the upper cylinder 7, and to accomplish this, 45 the said cylinder head 11 is provided with depending L-shaped lugs 12 that are engageable with L-shaped notches 13 formed in the upper portion of said upper cylinder 7. The lugs 12 on the head 11 are duplicates of 50 the lugs 9 on the cylinder 7, and the notches

13 in the cylinder 7 are duplicates of the notches 10 in the cylinder 8.

The cylindrical flange of the cylinder head 11 is of the same diameter as the cylinders 60 7 and 8, so that it fits freely around the extreme upper end of the carton A. As shown, the cylinder head 11 is reinforced by a metal disc 14 soldered or otherwise rigidly secured thereto and provided with openings 15 that permit the escape of air in the filling of 65 the carton and observation of the filling operation. Here it should be stated that the openings 15 are also in the web of the cylinder head proper. The cylinder head is provided with an axially projecting rigidly attached stem or handle 16 terminated in a cross bar 17.

When the cylinder head is removed, the 70 carton is adapted to be inserted into the cylindrical casing made up either of the two 75 cylinders 7 and 8 or of the cylinder 8 alone, and moved downward against a stop flange or shoulder 18 formed by a metallic collar 19 set into the lower end of the cylinder 8 and there secured by soldering, sweating, or otherwise. The interior diameter of the collar 19 is not less and may be slightly greater than the internal diameter of the carton A. Said collar 19 is preferably shouldered and 80 extended flush with the exterior of the cylinder 8. At its lower or projecting edge, the collar 19 is formed with serrations or teeth 20, several of which are slightly bent outward and some of which are slightly bent inward, so that they are given a "set" much 85 like the teeth of a saw. These teeth, under rotation of the casing, will cut an annular or cylindrical groove in a cake or mass of ice-cream that is slightly wider than the combined thickness of the casing and carton completely filled with ice-cream. While 90 the ice cream acted upon by these teeth will not actually be forced out of the groove cut by the teeth, the cream acted upon by the teeth will, nevertheless, be softened up so 95 that the cylindrical casing may be easily forced through the same. In fact, the cream thus loosened up seems to act more or less as a lubricant or, at any rate, such softened material can be readily displaced when the 100 cylindrical casing is forced through the body of cream. The sharpness of the teeth 20 also makes it an easy matter to force the device into the ice-cream to fill the carton.

Figs. 1 and 2 show the device with the two 110

cylinders 7 and 8 interlocked and with the cylinder head interlocked to the cylinder 7, thereby adjusting the device to hold a large size or quart-holding carton. When the device is to be used to hold a short carton, such as a pint-containing carton, the cylinder 7 is removed and the cylinder head will then be directly interlocked to the cylinder 8. It is important to note that, in any and all of the arrangements, the external surface of the casing and of the cylinder head are flush and present a smooth exterior surface.

The numeral 21 indicates a combined clamp and scraping ring, being preferably formed from square wire bent to form a spring ring with outturned ends 22. This ring 21 is of a size to quite freely engage the exterior of the metal casing and, normally, it may be held on the flange of the cylinder head 11 by spring clips 23 shown as applied to the latter. Should any ice-cream adhere to the exterior of the casing, it may be readily removed by forcing the ring 23 downward while frictionally holding the same under light pressure produced by pressing together more or less the ends 22. Also, this split ring may be used to clamp and hold either of the cylinders or case sections 7 or 8, while connecting or disconnecting the same.

Attention is called to the fact that in Fig. 6, the ring 21 is shown as of slightly smaller scale than in Figs. 1 and 2.

As is evident, when a carton has been filled and its cylinder head removed, such filled carton may be readily engaged by the fingers and removed from the casing. In practice, it has been found that the filling operation may be performed very rapidly and satisfactorily.

The device is herein designated as an ice-cream carton filler, but, as is evident, it may be used for other or similar purposes.

What I claim is:

45 1. An ice-cream carton filler comprising a plurality of detachably connected coincident cylindrical sections having interlocking joint-forming elements located within the cylindrical space common to the said sections.

50 2. An ice-cream carton filler comprising a cylinder adapted to contain a carton and provided at its receiving end with serrations or teeth adapted to cut a cylindrical groove 55 to receive the casing and carton therein con-

tained, said casing at its receiving end having a stop limiting the downward movement of the carton, and a handle-equipped head detachably applicable to the upper end of said casing, the said casing being made up 60 of detachably connected sections.

3. An ice-cream carton filler comprising a cylinder adapted to contain a carton and provided at its receiving end with serrations or teeth adapted to cut a cylindrical 65 groove to receive the casing and carton therein contained, said casing at its receiving end having a stop limiting the downward movement of the carton, and a handle-equipped head detachably applicable to the 70 upper end of said casing, said casing being made up of sections, said sections and said head having interlocking elements whereby the two sections may be detachably connected and the head detachably connected 75 to the upper section, or the upper section may be removed and said head detachably connected to said lower case section.

4. An ice-cream carton filler comprising a cylindrical shell made up of cylindrical 80 sections and a head, said sections having interlocking engagement and the said head having interlocking engagement with either of said cylindrical sections.

5. An ice-cream carton filler comprising 85 a cylindrical shell made up of cylindrical sections and a head, said sections having interlocking engagement and the said head having interlocking engagement with either of said cylindrical sections, one of said cylindrical sections having a cutting edge at 90 its receiving end, also said sections lying within a common cylindrical space.

6. An ice-cream carton filler comprising a cylinder adapted to contain a carton and provided at its receiving end with teeth and above the teeth with an inwardly projected stop ledge for limiting the downward movement of the carton, the said teeth having a cutting width at least as great as the radial 95 thickness of said cylinder and its stop ledge, whereby said teeth will cut an annular groove wider than the combined thickness of said casing and the carton therein contained.

7. The structure defined in claim 6 in 100 which said teeth are beveled circumferentially in both directions from their cutting points.

In testimony whereof I affix my signature:
BURTON L. HUNTLEY.
